UNITED STATES PATENT OFFICE.

WILL D. PARKER, OF BARTLESVILLE, OKLAHOMA, ASSIGNOR OF ONE-HALF TO RAY L. STURM, OF BARTLESVILLE, OKLAHOMA.

AIRPLANE PROPELLER.

1,404,403.

Specification of Letters Patent. Patented Jan. 24, 1922.

Application filed January 12, 1921. Serial No. 436,738.

To all whom it may concern:

Be it known that I, WILL D. PARKER, a citizen of the United States, residing at Bartlesville, in the county of Washington and State of Oklahoma, have invented certain new and useful Improvements in Airplane Propellers, of which the following is a specification, reference being had to the accompanying drawings.

10 It is the purpose of the present invention to provide an airplane propeller, wherein, as the power of the engine is increased likewise increasing the peripheral speed of the motor shaft, the pitch of the 15 propeller blades will correspondingly automatically vary, thereby causing a maximum air displacement and relatively increasing the pulling power of the blades to the engine.

20 Another purpose is to provide a device of this character including means for simultaneously and automatically increasing the radial length of the blades and relatively increasing the angular pitch of the blades, 25 as the operating means is increased.

Still another purpose involves an airplane propeller, wherein the blades assume a minimum angular pitch relatively to the minimum speed of the motor, so that when 30 the power of the motor is increased, the angular pitch of the propeller blades will correspondingly increase, so as to increase the pulling power of the propeller relatively to the engine, there being means for governing such action of the propeller, according to the peripheral speed of the motor 35 shaft.

A further purpose is to provide an airplane propeller, wherein the blades are movable axially outwardly through centrifugal force, in combination with means for resisting this force correspondingly to the minimum power of the motor, and maintaining the blades at a minimum angular pitch. As the motor shaft increases in power, the governor is actuated, thereby lessening the resistance relatively to the centrifugal force, allowing the propeller blades to assume different angular pitches.

While the design and construction at present illustrated and set forth is deemed preferable, it is obvious that as a result of a reduction of the invention to a more practical form for commercial purposes, the invention may be susceptible of changes. 55 and the right to these changes is claimed, provided they are comprehended within the scope of what is claimed.

The invention comprises further features and combination of parts, as will be herein- 60 after set forth, shown in the drawings and claimed.

In the drawings:—

Figure 1 is a view in section of a housing or casing, with a propeller shaft and 65 motor in elevation, showing parts of the pitch governing means for the propeller in elevation, showing the propeller blades in dotted lines and in dot and dash lines, the dotted lines representing the blade beyond the casing, while the dot and dash line represent the blade (which is not visible according to the character of view) which is to this side of the casing, and also showing the blades assuming a minimum pitch. 70

Figure 2 is a similar view showing the blades assuming an increased angular pitch. 75

Figure 3 is a sectional view on line 3—3 of Figure 1, more clearly showing the construction of the connections of the propeller blades, and also illustrating the interior structure of the casing carried by the motor shaft.

Figure 4 is an enlarged detail view of an arm which is carried by the connector of the shank of the propeller blade.

Figure 5 is a detail view of a portion of the casing or housing and showing parts of the ring plates 17 and 18.

Referring to the drawings, 1 designates a portion of a motor and 2 denotes the motor shaft, while 3 designates a housing or casing, which is rotatable with the shaft. The disc wall 4 of the housing has an opening 5 and provided with a hub, and through which the motor shaft extends. The motor shaft 2 has a shoulder 6 against which the casing or housing engages. The hub 7 has

its flange 8 secured to the disc wall of the housing or casing as at 9.

A governor body 10 is threaded upon the motor shaft in contact with one end of the hub, so as to bear against the hub and hold the casing or housing against said shoulder, whereby the governor body, the casing or housing and all other parts may rotate with the motor shaft.

- 10 This casing or housing has an angular wall 11 including an inturned flange 12, which is in parallelism with the disc wall 4. A suitable nose plate or cover 13 is bolted or otherwise secured at 14 to the inturned flange 12, 15 to insure a complete housing or casing for the mechanism for changing the pitch of the propeller blades.

Fixed to the disc wall 4 of the housing or casing by the nuts 15 and correspondingly 20 connected to the inturned flange 12 by the nuts 15^a are rods 16. These rods are arranged at intervals preferably four in number, though it is obvious that any number of rods may be employed, and act as supports 25 and guides for the ring plates 17 and 18. The ring plate 18 is automatically movable and guided upon the rods 16, while the ring plate 17 is, under ordinary circumstances, stationary. The rods 16 are threaded as 30 shown, and engaging said threads are nuts 20 and 21, which may be adjusted, for adjusting the ring plate 17 relatively to the ring plate 18.

The governor body 10 has a set bolt 22 for 35 engaging into the hub, for holding the governor body relatively to the hub.

The nose plate 13 for the casing which carries the propeller blades may be any suitable contour, preferably as shown, for instance substantially frusto-conical shape, 40 and may be constructed of any suitable metal preferably cast aluminium. The extreme nose of this plate 13 has an opening 23 for the reception of the extreme end of 45 the governor body 10, tending to steady or stabilize the entire structure.

The governor body is provided with diametrically opposite radial arms 24, to which the levers 25 are connected. One end of each 50 of these levers 25 carries a ball 26, while its other end is connected to a link 27. This link is in turn connected to a turn buckle 28, links 29 are connected to the turn buckles, and are in turn pivotally connected at 30 to 55 the movable ring plate 18.

The casing or housing is provided with offset extension tubes 29^a, which have internal spiral threads 30^a, which are engaged by the spiral threads 31 on the exterior of 60 the shanks of the propeller blades 32. The shanks of the propeller blades have rectangular bores 33 in which the sliding connectors 34 engage.

The hub 7 is provided with diametrically 65 opposite radial lugs 35, to which the rods 36

are connected, there being loosely arranged cushioning washers 37 and the nuts 38 and 39 for connecting the rods 36 to the lugs. The rods 36 are in turn threaded at 40 into the connectors 34, there being lock nuts 41 to hold the rods 36 relatively to the connectors. 70

Arms 42 are provided, and these arms have shanks, which pass through the connectors and are provided with nuts 43 to hold the arms relatively to the connectors. It will be 75 noted that the rods 36 thread into the ends of the connectors, and are held from turning by the lock nuts 41. The arms 42 are shaped or curved not only as shown in Figure 3, but are also extended toward the 80 disc wall 4 of the casing or housing, so that the extremities of the arms may engage between the ring plate 18 and the disc wall 4 of the casing or housing.

Coiled expansion springs 44 are interposed between the ring plates 17 and 18, there being lugs on the plates to hold the springs in place. Where the connectors are connected to the lugs 35 expansion coiled 90 springs are omitted, to afford spaces of diametrically opposite portions, to make room for said connections.

The ring plate 17 is adjusted, to tension the coiled springs 44, whereby sufficient pressure of the ring plate 18 may be exerted on the arms 42, to hold the propeller blades 32 at a minimum angular pitch, according to the minimum peripheral speed of the motor shaft. 95

When the power of the motor is increased, thereby relatively increasing the peripheral speed of the motor shaft, the propeller blades tend to unscrew and move axially outward, due to the centrifugal force and the air resistance on the blades. When the motor shaft increases in its peripheral speed, the balls of the governor body swing outwardly, thereby pulling upon the links and turn buckles and also pulling upon the ring plate 18, the coiled expansion springs 44 resisting the action. Under the action of the governor in this manner, the ring plate 18 is allowed to move permitting movement of the arms 42, and since the arms 42 are connected to the shanks of the propeller blades, 110 the blades will assume a greater degree of angular pitch, according to the increased peripheral speed of the motor shaft, thereby increasing the pulling power of the blades relatively to the speed of the motor.

Should the propeller be operating 1400 revolutions per minute and assuming the air pressure on the rear surfaces of the propeller blades at 800 pounds for both blades (400 pounds each), and then assuming 400 pounds pressure in centrifugal force tending to unscrew the blades axially outwardly, (the centrifugal force having been found to exert a very little force against the arms 42 on account of the comparatively sharp angles of

the spirals), there is a total of 1200 pounds tending to unscrew the blades or increase the pitch.

A counteracting force of 1200 pounds pressure is exerted on the arms 42 through the medium of the expansion springs.

It is then obvious that at 1400 R. P. M., the blades have 1200 pounds of pressure on each side and are neutral. A very few extra 10 pounds of pressure will be necessary to move the arms and increase the pitch. Therefore when the power of the motor is increased, after the airplane has ascended (all airplane 15 motors are as a rule speeded up from 50 to 200 R. P. M., as the plane ascends and gains speed), the governor will then expand tending to pull the ring plate 18 from the arms and at the same time the centrifugal force becomes greater due to the increase speed 20 tending to unscrew the blades and increase the pitch. When the ring plate 18 is pulled away from the arms, the arms naturally follow the plate due to the force of the air against the rear surface of the blades. In 25 case the motor slows down the reverse of these conditions is true and the pitch of the blades decreases, giving more power in a climb.

Washers 34^b are mounted upon connectors 30 so as to contact with the arms 42 and the nuts 43, there being heavy tension coiled springs 34^a interposed between the washers 34^b and the inner ends of the shanks of the blades tending to force the blades inwardly 35 to counteract the centrifugal force.

These springs 34^a work in connection and perform the same functions as the springs 44. In fact one of these springs has one end attached to its respective connector, and its 40 opposite end is connected in any suitable manner to the inner extremity of the shank of each blade, hence acting to draw the blade inwardly against the centrifugal force.

While Will D. Parker and Ray L. Sturm 45 are herein named as sole inventor and assignee respectively, they are named as joint inventors in the application for patent on an airplane propeller filed June 15, 1918, Serial No. 240,363, and since this present case contains claims substantially the same as those 50 in the prior application, the present case is a continuation of said prior application.

The invention having been set forth, what is claimed as being useful is:

55 1. The combination with a propeller having blades rotatably and longitudinally movable with respect to the propeller axis, of means for automatically permitting rotation of the blades to vary their angular pitch, and means for permitting the blades to move axially outwardly from the propeller axis 60 simultaneously with the rotation of the blades, as the speed of the propeller increases, and means connected to the center of the hub of the propeller and connected

axially to the propeller blades and including abutment means tending to resist said rotation of the blades to insure preventing excessive pitch changing of the blades.

2. The combination with a propeller including blades rotatably and longitudinally movable with respect to the propeller axis, of a governor controlled means for automatically permitting rotation of the blades to vary their angular pitch. 70

3. The combination with a propeller including blades rotatably and longitudinally movable with respect to the propeller axis, of a governor controlled means for automatically permitting rotation of the blades 80 to vary their angular pitch, and means for permitting outward axial movement with respect to the propeller axis simultaneously with the rotating of the blades, as the speed of the propeller increases. 85

4. The combination with a propeller including blades rotatably and longitudinally movable with respect to the propeller axis, of a governor controlled means for automatically permitting rotation of the blades 90 to vary their angular pitch, said means including means to yieldably retard the rotative movements of the propeller blades.

5. The combination with a propeller including blades rotatably and longitudinally 95 movable with respect to the propeller axis, of a governor controlled means for automatically permitting rotation of the blades to vary their angular pitch, and means for permitting outward axial movement with 100 respect to the propeller axis simultaneously with the rotating of the blades, as the speed of the propeller increases, said first named means including means to yieldably retard the rotative and outward axial movement of 105 the blades.

6. The combination with a propeller including blades rotatably and longitudinally movable with respect to the propeller axis, of a governor controlled means for automatically permitting rotation of the blades to vary their angular pitch, and means for permitting outward axial movement with respect to the propeller axis simultaneously 110 with the rotation of the blades, as the speed of the propeller increases, said first named means including means to yieldably retard the rotative and outward axial movement of the blades, and means to regulate the yieldable means. 115

7. In a device for the purpose indicated, a propeller body, a rotating shaft therefor, propeller blades connected to the body with their axis in offset positions to the shaft, means connected to the center of the body 125 and having an axially slid able connection with the propeller blades, resilient means, centrifugal means controlling the resilient means, and abutment members carried by the means which is axially joined with the 130

propeller blades and cooperating with the resilient means to permit rotation of the blades to vary their angular pitch.

8. The combination with a propeller having blades rotatably and longitudinally movable on their axis disposed offset upon diagonally opposite sides of the propeller case, means to resist the rotation and longitu-

dinal movement of the blades, ad means operated through the medium of said centrifugal force, to operate the resisting means to permit rotation of the blades to vary their angular pitch.

In testimony whereof I hereunto affix my signature.

WILL D. PARKER.
